UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR A FRONT OF A STORE-BUILDING.

SPECIFICATION forming part of Design No. 19,489, dated December 17, 1889.

Application filed November 19, 1889. Serial No. 330,899. Term of patent 3½ years.

To all whom it may concern:

Be it known that I, ANTOINE LACROIX, Jr., of the city of Brooklyn, in the county of Kings and State of New York, have invented a new and original Design for the Front of a Store-Building, of which the following is a specification, reference being had to the accompanying drawings, forming a part thereof.

Figure 1 represents a front elevation of a store-building illustrating my design. Fig. 2 represents a plan or horizontal section of the first story of the building, and Fig. 3 a plan or horizontal section of the second story thereof. Fig. 4 represents a vertical profile section of the front of the building, taken in the line *xx* of Figs. 1, 2, and 3. Fig. 5 represents a vertical profile section taken in the line *yy* of Figs. 1, 2, and 3. Fig. 6 represents a vertical profile section taken in the line *zz* of Figs. 1, 2, and 3. Figs. 1, 4, 5, and 6 are on the same scale, and Figs. 2 and 3 are on a smaller scale.

Similar letters of reference designate corresponding parts in all the figures.

This design embraces three stories of a building, the first story having a wide quadrangular bay which includes two store-fronts and a central vestibule, and the second and third stories having two octagonal bays, the lower parts of which are connected by a central balcony on the second story and are connected with the main portion of the front by means of corbels, the upper part of the front above the bays having a straight cornice, which is surmounted by a central pediment, on the opposite sides of which are inverted consoles, all as hereinafter more particularly described in detail with reference to the drawings.

A designates the main portion of the front, of which the sides and center are flat.

B B designate the wide quadrangular bays of the first story, which include the two store-fronts *a* and the central vestibule *b*. At opposite sides of these bays B are doors C, substantially flush with the front main wall A.

D D' D D' are the quadrangular bays which run up through the second and third stories. D D designate the parts of each of the bays in the second story, and D' D' designate the parts in the third story.

E designates the central balcony on the second story between the bays D D. A cornice *c*, which runs along the upper edge of this balcony, is continued along the bays D D, and under this cornice at the outer portions of the bays are two corbels *d*.

F is a straight cornice which runs along the upper flat main wall of the building above the bays D' D'. G is the pediment arranged centrally above the said cornice, and H the inverted consoles at the sides of the said pediment. The pediment G is finished off in pedestal form at the ends, as shown at *e* in Fig. 1, and between these pedestal-formed parts is an arch *f*. The face of the pediment between the pedestal-like portion *e* and the arch *f* is ornamented with foliated and scroll work *g h i*, as shown in Fig. 1.

What I claim is—

The design for the front of a store-building, substantially as herein shown and described.

ANTOINE LACROIX, JR.
